UNITED STATES PATENT OFFICE

JAMES OSCAR CRAWFORD, OF ADAMS, TENNESSEE

TYPEWRITER ATTACHMENT

Application filed January 6, 1931. Serial No. 506,963.

This invention relates to improved attachments for typewriters of the form generally employed for clerical and office work in general, and the invention has reference to a simple appliance constituting a copy holder and designed to accommodate different characters of work in a manner to facilitate copying by the operator of the machine.

Briefly stated, the inventive conception comprehends a structure characterized by a work supporting and guiding rack disposed in a substantially horizontal elevated position and means for attaching said rack to a conventional typewriter without requiring alteration of the existing or stock parts of the typewriter machine, said means being such as to suspend the rack at a point with respect to the keyboard to expedite and facilitate copying while the copy of the work is held in a convenient position for such service.

A novel feature is found in the utilization of a rack including a substantially horizontally extending ledge and an associated back-ing member wherein said member includes vertically spaced longitudinally disposed parallel slats or strap members whereby to permit convenient copying from a book supported on said ledge or convenient copying from relatively long legal sheets, the latter feature being desirable in that it permits the sheet to be "threaded" through the slats in a position to hold it rigidly and to allow it to be fed by hand in a step by step manner.

A further point of novelty is predicated upon the multiple wire rod harness structure which constitutes the means for attaching the rack to the typewriter.

In the drawings:

Figure 1 is an end elevational view of a conventional typewriter showing the copy holder in operative position thereon.

Figure 2 is a fragmentary top plan view of one end portion of the rack.

Figure 3 is a view like Figure 1 observing the structure from the opposite end of the machine with respect to that shown in Figure 1.

Figure 4 is a vertical sectional view centrally through the rack.

Figure 5 is a rear elevational view of the

complete appliance for attachment on the machine.

In the drawings, the typewriter is generally designated by the numeral 6 and the back or rear feet are indicated at 7 and the front feet distinguished by the characters 8.

The attachment comprises two primary parts, namely, the work supporting rack 9 and the attaching frame-work which is chiefly made up of a pair of duplicate end frames 60 10 and 11 respectively.

This attaching device as a whole may be said to be composed of a multiplicity of wire rods attached together and assembled to form a sort of a harness to embrace the typewriter.

Observing the end members from the rear as seen in Figure 5, it will be seen that the major part of each member is formed from a single length of wire which includes a lower vertical leg portion 12 having an eye 13 formed at its bottom embracing the adjacent support or leg 7. The upper end of the part 12 is bent laterally outward in a horizontal line as at 14 and bent at right angles and vertically as at 15 and then bent forwardly 70 to provide a suspension arm 16 which overlies the typewriter as seen in Figure 1.

The numeral 17 designates a sort of a diagonal brace attached at its upper end to the arm 16 and at its lower end to the leg 12 80 adjacent the eye 13. The numeral 18 designates a substantially diagonal stay which at one end wraps around the portion 14 as indicated at 19 to provide a pivotal connection which has its forward end formed with an eye 20 to embrace the front legs 8 of the typewriter.

The numeral 21 designates a tie rod between the two end members connected at its opposite ends to the leg 12 and which forms a connecting brace as shown in Figure 5. It may thus be said that the so-called harness is made up of a pair of duplicate end members including a single length of wire bent to provide the arms 16 for supporting the rack 9 and the remaining portion bent to provide attaching means for the feet 7 a pair of attaching stays 18 and bracing means for the end members.

The rack 9 is of a composite structure and

is characterized by a substantially U-shaped member whose end portions are denoted by the numerals 22 and whose bight portion is indicated by the numeral 23. The ends of the 5 portions 22 are wrapped around the arms 16 as shown in Fig. 4 and the forward ends of these arms 16 are connected together by the bar 16' as shown in Fig. 2. As before implied a plurality of longitudinal metal straps 24 10 are provided and these have their end portions 25 curled around the portions 22. The uppermost strap or slat 26 has its upper longitudinal edge 27 bent around the bight as indicated in Figure 4, and the ledge comprises 15 a horizontal shelf 28 and a substantially vertical portion 29, these parts 28 and 29 having bent knuckles 30 and 31 bent around the adjacent portion. For instance, the knuckles 31 embrace the portions 22 while 20 the knuckles 30 embrace the extremities of the aforesaid arms 16. Consequently, the ledge of this rack constitutes the means for mounting the rack, as a unit, on the arms 16. The slats 24 and 26 constitute backing members 25 for the work.

The work may be a book which can be rested in the ledge and backed by the members 24 and 26. As before indicated however, it is possible to use long sheets of copy papers 30 which may be passed upwardly through the several slats in a sort of threaded manner so that the sheet of paper may be held frictionally in place at the same time pulled by hand gradually upward as the copying work 35 proceeds until the end of the sheet is reached.

To facilitate this maintenance of long legal sheets in the rack, I provide a clamping plate 32 held in place by retaining bolts 33 and thumb nuts 34. The lower edge or 40 lip 35 may be offset outwardly to facilitate insertion of the sheet of paper therebeneath. This clamping plate 32 comes in handy when using relatively short flexible sheets in the rack. In other words it aids in holding the 45 sheet nicely in place and the clamping plate 32 need be tightened only slightly so as to hold the paper frictionally and to permit it to be pulled up between the plates 32 and adjacent flaps or backing straps 26.

50 The numerals 36 designate end clips whose side portions are formed with coiled springs 37 embracing the portion 22 and anchored behind the slats 24 and 26 as indicated in Figure 4.

In practice, the eyes 13 are placed around the rear feet 7 of the typewriter and the stays 18 are swung down on their pivotal connection 19 and the eyes 20 are engaged 55 around the front feet 8. This attaches the supporting frame on the typewriter so that the arms 16 overlie the machine as shown in Figure 3. This places the rack 9 in a convenient position to accommodate various 60 kinds of copywork to expedite copying while

holding the work in a convenient plane position.

It is thought that the description taken in connection with the drawings will enable a clear understanding of the invention to be had. Therefore, a more lengthy description 70 is thought unnecessary.

While the preferred embodiment of the invention has been shown and described, it is to be understood that minor changes coming within the field of invention claimed may be resorted to if desired. 75

I claim:

1. In a copy holder of the class described, 80 a rack, and means for attaching the rack to a typewriter, said rack comprising a substantially U-shaped member, a plurality of spaced parallel horizontally disposed strap members carried thereby, and a forwardly projecting substantially horizontal shelf, 85 said shelf comprising a substantially right angular sheet of metal having a vertical portion provided with knuckles at its opposite ends embracing the adjacent portions of the U-shaped member, and a horizontal portion 90 formed at its opposite ends with tubular knuckles to embrace the end portions of arms of the aforesaid attaching means.

2. In a typewriter attachment of the class described, 95 an attaching device embodying a pair of longitudinally spaced parallel suspension arms adapted to overlie the typewriter, and a rack including a vertical backing structure and a horizontal shelf portion, said horizontal shelf portion having its ends 100 formed into tubular knuckles, said knuckles embracing the forward end portions of said arms, whereby to connect said rack to said arms.

3. In a copy holder of the class described, 105 a work-supporting rack, and means for attaching said rack to a typewriter, said rack comprising a substantially vertical backing structure including a plurality of spaced parallel vertically disposed backing slats 110 and a substantially horizontal ledge provided with tubular attaching knuckles at its opposite ends, a clamping strip attached to the uppermost slat, binding nuts associated with said strip for holding it frictionally 115 against the paper, and a pair of spring clips mounted on the end portions of the rack and adapted to co-operate with the clamping strip to aid in holding the work in place.

4. In a work-holder of the class described, 120 a work-supporting rack, and an attaching harness therefor, said harness being composed of a plurality of wire rods fastened together, the end portions of certain of said rods being formed with terminal eyes 125 adapted to releasably embrace supporting feet on the base of the conventional typewriter so as to hold said harness securely in place.

5. In a copy holder of the class described, 130

a rack, and an attaching harness therefor comprising a pair of duplicate end members, each end member including a vertical portion provided at its bottom with an attaching eye, and a horizontal rack-supporting arm, together with a forwardly and downwardly inclined stay formed at its forward end with an eye to embrace the adjacent foot on the base of a typewriter, a tie rod connecting the forward ends of the arms together and a shelf-forming member having its ends connected with the forward ends of the arms in front of the rack.

In testimony whereof I affix my signature
15 JAMES OSCAR CRAWFORD.
